UNITED STATES PATENT OFFICE.

FANNY M. DANIELS, OF SOMERVILLE, MASSACHUSETTS, ASSIGNOR TO DENNISON MANUFACTURING COMPANY, OF BOSTON, MASSACHUSETTS, A CORPORATION OF MASSACHUSETTS.

DESIGN FOR TRIMMING.

No. 39,147.

Specification for Design.

Patented Feb. 18, 1908.

Application filed December 30, 1907. Serial No. 408,710. Term of patent 14 years.

To all whom it may concern:

Be it known that I, FANNY M. DANIELS, a citizen of the United States, residing at Somerville, in the county of Middlesex and State of Massachusetts, have invented a new, original, and ornamental Design for Trimming, of which the following is the specification, reference being had to the accompanying drawing, forming part thereof.

The figure is a perspective view of the trimming, showing my new design.

I claim:

The ornamental design for trimming, as shown.

FANNY M. DANIELS.
